POWER DISPLAY DEVICE

Jack Marak, New York, N. Y.

Application May 18, 1942, Serial No. 443,343

7 Claims. (Cl. 40—126)

This invention relates to new and useful improvements in a power display device.

The invention proposes a power display device which is characterized by a container for a fluid substance from which a driven pump may pump the fluid substance to an elevated display tank having a bottom valve controlled discharge from which the fluid may pass to a storage tank which is also provided with a bottom valve controlled discharge and thence to a water wheel which is located above the container and driven with the fluid from the storage tank, which fluid then enters the container and is repumped to said elevated display tank.

It is proposed that the elevated display tank be transparent and be provided with certain floats, and mechanism to cause the floats to rise and fall in a certain way. Advertising material may be carried by these floats and be displayed.

Furthermore, an arrangement is proposed for driving the power display device. One or more transmissions are also provided which are driven by the power display device, and which may be connected with other apparatus as desired.

For further comprehension of this invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of a device constructed in accordance with this invention.

Fig. 2 is a perspective view of a crank shaft used in the device.

Fig. 3 is a fragmentary enlarged elevational view looking in the direction of the line 3—3 of Fig. 1.

Fig. 4 is a fragmentary enlarged sectional view taken on the line 4—4 of Fig. 3.

Fig. 5 is an enlarged fragmentary vertical sectional view of a portion of the elevated display tank disclosing details of the float.

Fig. 6 is a fragmentary view similar to Fig. 5 but showing the top portion of the tank with the float at the top.

Fig. 7 is a fragmentary enlarged detailed view of a portion of Fig. 5, illustrated with certain parts removed.

Fig. 8 is a fragmentary enlarged horizontal sectional view taken on the line 8—8 of Fig. 5.

Fig. 9 is an enlarged detail view of a portion of Fig. 5 completely in section.

Fig. 10 is a schematic wiring diagram of the device.

The power display device, in accordance with this invention, includes a container 10 for a fluid substance. An elevated display tank 11 having a bottom valve controlled discharge 12 for fluid substance is located above the container 10. A driven pump 13 is provided for pumping said fluid substance from said container 10 to said tank 11. A storage tank 14 is supplied with fluid substance from the said bottom discharge 12 of the display tank 11. A water wheel 15 is located above the container 10 and is driven with fluid from said storage tank 14, which fluid then enters the tank 10 and is repumped by the pump 13 to the elevated display tank 11. In this way the fluid substance keeps circulating.

There is a transmission system 16 from the water wheel 15 to the said pump 13. An electric motor 17, or other supply of power, is connected in with this transmission system, to supply the necessary power to keep the display device working. The said display tank 11 is provided with a plurality of floats 18 which are so constructed and associated with mechanism that they will float and sink in succession. Each float 18 has one or more top valves 19 and a bottom valve controlled discharge 20 aligned with the said bottom valve controlled discharge 12, in the bottom position of the float. There is means for opening the top valve or valves for a short period when the float is at the top of said display tank 11 so that it takes in fluid and sinks. Means is also provided for opening said bottom valve controlled discharge, for a short period when the float is at the bottom of the display tank so that it loses its fluid and rises to the top of the display tank. This continues during the entire period of operation of the power display device. A plurality of transmissions 21 are operatively connected with the floats 18 to transmit some of the power which may be utilized as desired to drive other displays, or for other purposes.

The container 10 forms a bottom base for the power display device. The other parts thereof are mounted directly or indirectly on this base. The elevated display tank 11 is supported on a large angle member 22 which is mounted upon the side of the storage tank 14. The storage tank 14 is supported by feet 23 upon the top of the container 10. The pump 13 is connected by a storage conduit 24 with the container 10 so that it may pump the fluid substance from the container 10 through the pump discharge 25, into the top of the elevated display tank 11. The

words "Lefto," "Centro," "Righto" appearing upon the sides of the floats 18 are intended to indicate advertising material which is visible through the transparent material of the tank 11.

The storage tank 14 has a discharge 26 which is directed against the water wheel 15. The construction is such that the water wheel 15 will be driven by the fluid which leaves the tank 14. The water wheel 15 is supported on a bracket 27, which in turn is supported on or across the tank

19. The water wheel 15 is provided with a driven shaft 28, which in turn has a bevel gear 29 fixed thereon. This bevel gear meshes with a bevel gear 30 on a vertical shaft 31 rotatively supported on the bracket 27. The vertical shaft 31 is provided with a bevel gear 32 meshing with the bevel gear 32' on one end of a crank shaft 33 which forms a part of the transmission 16. This crank shaft 33 is supported at several points. There is a bearing 34 supporting one end of the shaft 33. This bearing is in turn supported on the bracket 27. Another bearing 35 supports an intermediate portion of the crank shaft 33. Another bearing 36 supports the other end of the crank shaft 33. The crank shaft 33 has large cranks 33^a which may be connected with other display devices or other devices. The crank shaft 33 also is provided with smaller cranks 33^b which may also be utilized to take off power, as desired.

The floats 18 are of hollow construction. Each float 18 is provided with a plurality of valves 19 at the top. These valves control passages 37 through the top of the float. Each valve 19 is mounted on a valve stem 38 which extends upwards and passes through a support bracket 39. Each support bracket 39 has perforations 40 to permit the circulation of fluid substance through or around the bracket. Each bracket 39 is provided with a dash pot 41 to make each valve 19 rapid opening and slow closing. Each dash pot 41 includes a closed container 42 mounted on the bracket 39. The valve stem 38 passes through the container 42. A piston 43 is located within the container 42 and fixed on the valve stem 38. The piston 43 has a large opening 44 which is controlled by a one way valve 45 having a small bleed 46. A spring 47 is located within the container 42 and urges the piston 43 upwards and thus urges the valve 19 into a closed position.

The top end of the valve stem 38 is provided with a head 48. Another spring 49 is coaxially mounted on the valve stem 38 and acts between the head 48 and the bracket 38 for assisting in urging the valve 19 into its closed position. Each valve head 48 is located directly below a lug 50 projecting from the top portion of the tank 11. The construction is such that when the float 18 reaches the top of the tank 11 the heads 48 strike the lugs 50, which indirectly opens the valves 19. The valves 19 will remain open for a preselected time, even though the float 18 starts sinking. The dash pots 41 control the length of time that the valves 19 remain open. During this period the fluid substance enters the interior of the float and this is what causes the float to sink.

Each float 18 is also provided with said bottom valve controlled discharge 20. This discharge is in the nature of a tube which is valve controlled. There is a valve stem 51 slidably mounted on spider supports 52 within this tube. A valve 53 is mounted upon the top of the valve stem 51. A spring 54 is coaxially mounted on the valve stem and acts between one of the spiders 52 and a collar 55 mounted on the valve stem. This spring

54 acts to urge the valve 53 into a closed position. The discharge 20 is aligned with one of the discharges 12 of the display tank 11. Thus when the float 18 is in a bottom position, as shown in Fig. 8, these discharges engage each other. In this position of the float the valve 53 will be open. The reason for this is that the lower end of the valve stem 51 then rests upon a member 56 mounted in the discharge 12. This raises the valve 53.

The member 56 is in the nature of a spider which is mounted on a valve stem 57. The valve stem 57 is provided with a valve 58 which works in cooperation with a perforated disc 59 mounted across the discharge 12. A spring 60 urges the valve stem 57 into a raised position, in which position the valve 58 is closed. However, when the valve stem 51 rests on the spider 56, the valve 58 will be opened in addition to the valve 53. Consequently, the fluid substance from the interior of the float 18 may discharge through the discharge 12. The discharges 12 are connected by a pipe 61 with the side of the storage tank 14. The pipe discharge 20 must actually enter the discharge pipe 12 before the valve 58 can open making it impossible for the storage tank 14 to empty directly through the discharge pipe 12.

Means is provided for latching each float 18 in its bottom position for a short period of time, which time is calculated to be sufficient to permit the float to completely lose its fluid substance. This means includes a solenoid 62 for each float. Each solenoid 62 has a core 63 which is connected with a bolt 64 adapted to engage a keeper slot 65 in the side of the discharge 20. A spring 66, see Figs. 8 and 9, normally urges the solenoid core 63 and hence the bolt 64 into a retracted position. The solenoid 62 is connected in a circuit 67 which includes a normally open switch 68 and a normally closed thermostat switch 69. The thermostatic switch 69 is formed of high resistance material, so that when the switch 68 is closed, closing the circuit 67, the current flowing through the material of the thermostatic switch 69 will create the required heat to cause the switch 69 to flex opening the circuit 69 after a certain period of time has elapsed.

A rod 70 is connected with the switch 68 and is movable by the float 18 to close the switch 68. Thus when the float 18 reaches its bottom position it strikes the rod 70, closing the switch 68 and thus the circuit 67. This energizes the solenoid 62 so that the bolt 64 engages the keeper 65, holding the float 18 in its bottom position. In this position the fluid substance is discharging. After a predetermined period of time a thermostat switch 69 breaks the circuit 67 which de-energizes the solenoid 62 and the spring 66 moves the bolt 65 to disengage the keeper 65. Immediately the float 18 starts rising and the valves 53 and 58 automatically close.

Each float 18 is associated with a transmission system 21. Each of these systems include a driven shaft 72 rotatively supported through a bracket 73. A gear 74 is loose on each shaft 72. A ratchet wheel 75 is fixedly mounted on each shaft 72. A spring pressed pawl 76 is mounted upon the side of each gear 74 and engages its ratchet wheel 75. A rack 77 meshes with the gear 74 and is mounted upon the top on the float 18. When a float 18 descends the rack 77 rotates the gear 74 which merely idles on the shaft 72. However, when the float 18 rises the rack 77 rotates the gear 74 in the opposite direction and the pawl 76 transmits these rotations to the ratchet

wheel 75 and thus to the shaft 72. The shaft 72 may be connected to drive various displays or other articles.

The crank shaft 33 is also provided with a bevel gear 78 which connects with a transmission system 79 connected with the motor 17. This transmission system 79 includes a crank 80 operating a connecting rod 81 which drives the pump 13.

Briefly, the operation of the device is as follows:

The motor 17 drives the transmission 79, which indirectly operates the pump 13. The fluid substance from the container 10 will be lifted by the pump 13 and discharged into the elevated display tank 11. The floats 18 will alternately ascend and descend, as previously explained. The fluid substance will discharge from the valve controlled discharges 12, and will pass through the pipe 61. The end of the pipe 61 which connects the discharges 12 is above the water line of the tank 14 as shown in Fig. 1, so that this pipe will be full of air. Thus, when the valves 53 and 58 are open as shown in Fig. 5 air will enter the float from the pipe 61 and adjacent discharge 12 to displace the water in the float and cause it to flow from the float emptying the same. When the latch is released the empty float will be buoyant to rise within its respective tank freeing the valves 53 and 58 to automatically close. From the pipe 61 the fluid substance will pass into the tank 14 and pass out through the discharge 26 and drive the water wheel 15. The fluid substance then collects in the container 10 from which it is recirculated as just explained. Rotations of the water wheel 15 will drive the transmissions 16 and 79. The electric motor 17 supplies any deficiency in power. The ascending and descending floats 18 will drive the various transmissions 21.

It is to be understood that the crank shaft 33 may be so arranged that it may drive the pump 13, without creating a dead center in the driving connecting rods, by having the crank arm portions 33a set 90° apart.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a power display, an elevated display tank having a bottom valve controlled discharge for fluid substance, means supplying fluid to said tank, a plurality of floats in said tank, each float having a top valve and a bottom valve controlled discharge aligned with said bottom discharge in the bottom position of said float, means for opening said top valve for a short period of time when the float is at the top of said display tank so that it takes in fluid and sinks, and means for opening said bottom valve controlled discharge for a short period of time when said float is at the bottom of said display tank so that it loses its fluid and rises to the top of said display tank.

2. In a power display, an elevated display tank having a bottom valve controlled discharge for fluid substance, means supplying fluid to said tank, a plurality of floats in said tank, each float having a top valve and a bottom valve controlled discharge aligned with said bottom discharge in

5 the bottom position of said float, means for opening said top valve for a short period of time when the float is at the top of said display tank so that it takes in fluid and sinks, and means for opening said bottom valve controlled discharge for a short period of time when said float is at the bottom of said display tank so that it loses its fluid and rises to the top of said display tank, said elevated display tank being transparent so that the floats are visible.

3. In a power display, an elevated display tank having a bottom valve controlled discharge for fluid substance, means supplying fluid to said tank, a plurality of floats in said tank, each float having a top valve and a bottom valve controlled discharge aligned with said bottom discharge in the bottom position of said float, means for opening said top valve for a short period of time when the float is at the top of said display tank so that it takes in fluid and sinks, and means for opening said bottom valve controlled discharge for a short period of time when said float is at the bottom of said display tank so that it loses its fluid and rises to the top of said display tank, the top valve of each float being resiliently urged closed, and a dash pot for controlling the closing time.

4. In a power display, an elevated display tank having a bottom valve controlled discharge for fluid substance, means supplying fluid to said tank, a plurality of floats in said tank, each float having a top valve and a bottom valve controlled discharge aligned with said bottom discharge in the bottom position of said float, means for opening said top valve for a short period of time when the float is at the top of said display tank so that it takes in fluid and sinks, and means for opening said bottom valve controlled discharge for a short period of time when said float is at the bottom of said display tank so that it loses its fluid and rises to the top of said display tank, the top valve of each float being resiliently urged closed, and a dash pot for controlling the closing time, and said means for opening the top valve comprising a stationary abutment which the valve strikes and then is self-opening.

5. In a power display, an elevated display tank having a bottom valve controlled discharge for fluid substance, means supplying fluid to said tank, a plurality of floats in said tank, each float having a top valve and a bottom valve controlled discharge aligned with said bottom discharge in the bottom position of said float, means for opening said top valve for a short period of time when the float is at the top of said display tank so that it takes in fluid and sinks, and means for opening said bottom valve controlled discharge for a short period of time when said float is at the bottom of said display tank so that it loses its fluid and rises to the top of said display tank, comprising abutments against which the valve strikes, and means for catching and holding the float in its bottom position to hold the valves open.

6. In a power display, an elevated display tank having a bottom valve controlled discharge for fluid substance, means supplying fluid to said tank, a plurality of floats in said tank, each float having a top valve and a bottom valve controlled discharge aligned with said bottom discharge in the bottom position of said float, means for opening said top valve for a short period of time when the float is at the top of said display tank so that it takes in fluid and sinks, and means for opening said bottom valve controlled discharge

charge for a short period of time when said float is at the bottom of said display tank so that it loses its fluid and rises to the top of said display tank, comprising abutments against which the valve strikes, and means for catching and holding the float in its bottom position to hold the valves open, said latter means comprising a solenoid operated catch and a thermostatic switch for opening the circuit through said solenoid.

7. In a power display, an elevated display tank having a bottom valve controlled discharge for fluid substance, means supplying fluid to said tank, a plurality of floats in said tank, each float

having a top valve and a bottom valve controlled discharge aligned with said bottom discharge in the bottom position of said float, means for opening said top valve for a short period of time 5 when the float is at the top of said display tank so that it takes in fluid and sinks, means for opening said bottom valve controlled discharge for a short period of time when said float is at the bottom of said display tank so that it loses its fluid and rises to the top of said display tank, a transmission operatively connected with each of said floats.

JACK MARAK.
